UNITED STATES PATENT OFFICE.

GERALD J. MACAURA, OF HARTFORD, CONNECTICUT.

MOVEMENT-CURE APPARATUS.

SPECIFICATION forming part of Letters Patent No. 716,448, dated December 23, 1902.

Application filed December 6, 1901. Serial No. 84,878. (No model.)

To all whom it may concern:

Be it known that I, GERALD J. MACAURA, a citizen of the United States, residing in Hartford, in the county of Hartford and State of Connecticut, have invented certain new and useful Improvements in Movement-Cure Apparatus, of which the following is a specification.

This invention relates to an improvement in movement-cure apparatus, it particularly relating to an improved surgical vibrator adapted to act in an especially effective manner upon any portion of the body to which it is applied, the object of the invention being to provide an improved device of this character effective when applied to the body to produce not merely a surface stimulation, but a penetrating effect, and this without irritating the nervous system of the patient.

In the drawings accompanying and forming part of this specification, Figure 1 is a view of one-half of a casing with this improved striker or beater in section. Fig. 2 is a transverse sectional view taken in the line *a a*, Fig. 1. Fig. 3 is a perspective view of this improved striker or beater; and Fig. 4 is an illustrative view of this improved striker in action, the dotted lines illustrating the position the yielding head assumes during its passage over the contact-plate.

The present improvement comprises in a general way a rotary beater or striker formed of a yielding material—such, for instance, as rubber—carrying one or more plate-engaging surfaces having, preferably, a metallic formation, each of said surfaces being free of pivotal connection with such body, but organized to yield in one direction when in contact with the plate. In the form shown the beater or striker is intended to be connected with suitable power, such as an electric or other suitable motor, for imparting movement thereto. In the present instance this improved beater or striker is mounted in a suitable casing 2, which may be of any desired formation. In one form thereof it is made up of two half members or sections 3 4, open at its under side, such sections being suitably bolted together at its front and rear lower edges and secured together at its top with a suitable screw. Carried by the casing for movement relatively thereto is a suitable

contact-plate 5, which is preferably of a fibrous material. It may, however, be of rubber or analogous material. This plate has 55 one end secured or hinged to the casing at the underside thereof, it being shown clamped in position against a shoulder 5' by a clamping member 6, having a pair of ears 7 overlapping the side walls of the casing and held 60 in position by one of the bolts which connect the two half members of the casing. This clamping member 6 will in practice be slightly curved in the direction of its length, so that it will exert considerable tension upon the 65 contact-plate, the front end of such clamping member being beveled or chamfered off, so that when the instrument is in contact with the body no rough surfaces will disturb the patient or interfere with the proper shifting 70 of the instrument. A suitable bur or projection 6', carried by the casing, projects into an opening in the plate to prevent the slipping of such plate out of its proper position. The beater or striker comprises a body formed 75 of a yielding material—such, for instance, as rubber—having a part thereof encircled by a metallic member constructed to shift the contact-plate, and in the present instance it is shown comprising a body 8, having a plurality 80 (shown as three, although any number may be used) of strikers 9, each comprising a head 9' and a neck 9". Each of these heads is so connected with the body, which may be of various sizes and formations, that while it will yield 85 relatively thereto it is free of joint and pivotal connections. In practice each of these heads is preferably covered by a suitable protector or cap, preferably metallic, which is curved in cross-section and whereby wear of 90 the strikers is resisted. This beater or striker may be composed of any suitable material which will permit the heads to yield sufficiently to pass properly over the contact-plate 5 when in use, but is preferably composed of 95 rubber of a suitable quality and condition, which, while permitting an effective striking of the contact-plate 5, will not appreciably retard the action of the beater or striker. In the form shown the beater or striker is provided 100 with a metallic core or sleeve 10, internally threaded for the reception of an externally-threaded portion of a shaft 12, shown provided with a shoulder 13, intermediate which and

one side of the beater or striker is placed a washer 14. Intermediate the opposite side of the beater or striker and a suitable clamping-nut is also located a washer. By threading the 5 sleeve 10 and shaft 12 the slipping of the beater or striker relatively to the shaft when in operation is prevented. This result can, however, be obtained in other well-known ways. One end of the shaft 12 is mounted in a suitable 10 bearing 15 in one side of the casing, while its opposite end is provided with an opening 16, into which projects a rotary core 17 of a flexible shaft 18, it being coupled therewith by a suitable fastening device, such as a screw 19. 15 The end of the flexible shaft carries an externally-threaded sleeve 20, turned into an internally-threaded socket 21, carried by the casing. The opposite end of this flexible shaft will be in practice connected with suitable power, such as an electric or other motor, which may be supported in any desired way, as by being swung from a ceiling or secured rigidly to the wall or floor or fastened to a hinged bracket. The casing is provided 20 with a suitable handle 22, which may be of flexible formation, if desired, shown projecting into a socket 23, by means of which the instrument is applied to the body.

In practice the operator grasps the handle 30 and applies the instrument in such manner as to bring the plate 5 into contact with the particular part of the body to be treated, whereupon the free end of the plate is shifted into engagement with the casing or as nearly 35 so as the operator may desire, according to the amount of vibration to be given the patient. The motor is then started, whereupon the beater or striker is rotated, and as each head thereof strikes the plate a vibratory effect is given to that portion of the body to which the device is applied, such vibratory effect depending, as just stated, upon the pressure with which the device is applied to the body. As each head successively engages 40 the plate the material of which the beater or striker is composed permits it to yield (and without producing a jerk) sufficiently to enable it to pass over such plate. By constructing the device of a resilient or springy material 45 a considerable amount of the metallic clang which would be present if the device were constructed entirely of metal is obviated, while at the same time the action of the beater or striker is such that without so much 50 harshness and pressure a much more penetrating effect is obtained, the vibration obtained, however, being of a soothing instead of an irritating quality. Furthermore, the organization of the present instrument is such 55 that the operator can apply the same without being affected by the vibration thereof.

By the provision of a number of heads or strikers located relatively close one to another a much more effective and constant action is 60 obtained. By forming the beater or striker of a flexible material vibration will be imparted to a patient with an entire absence of

harshness or metallic clang, while producing a deeper and more penetrating effect.

It is to be understood that the various details may be more or less modified without departure from the scope of my invention.

I claim as my invention—

1. In a surgical vibrator, the combination with a contact-plate, of a rotary striker comprising a body provided with one or more heads projecting therefrom and connected with such body for yielding movement when engaging said contact-plate, but maintained against movement independently of the body 75 when free of contact with said plate, and means for rotating said striker.

2. In a surgical vibrator, the combination of a striker having one or more heads formed of a resilient material, each provided with a 80 cap, and a contact member coöperating therewith.

3. In a device of the character specified, the combination of a contact-plate; means for supporting the plate; means for vibrating 90 the plate; means for actuating the vibrating means; and means independent of the actuating means and its casing for manipulating the device.

4. In a surgical vibrator, the combination 95 of a rotary striker comprising a body formed as one member with a circular head adapted to yield relatively to such body; a contact-plate in position to coöperate with the head; and means for rotating said striker.

5. In a surgical vibrator, the combination of a contact-plate, and a striker having one or more heads each provided with a cap adapted to engage said plate.

6. In a surgical vibrator, the combination 105 of a contact-plate; a rotary striker comprising a body of relatively large area, cut away to form one or more heads integral but yieldingly connected with such body, each of such heads having less area than such body; and means for rotating such striker.

7. In a surgical vibrator, the combination of a contact-plate and a striker comprising a body, and one or more heads integral but yieldingly connected with such body, each of 115 said heads having a metallic cap.

8. In a device of the character specified, the combination of a contact-plate; means for supporting the plate; means for vibrating the plate and comprising a body having a part 120 thereof constructed to impart motion to the contact-plate and encircled by a metallic member; and means for rotating the vibrating means.

9. In a surgical vibrator, the combination 125 with a casing, of a rotary striker mounted therein and comprising a body having one or more heads, each provided with a cap, and a movable contact-plate carried by such casing.

10. In a surgical vibrator, the combination 130 with a casing open at its under side and having a handle, of a rotary striker in said casing, and a swinging contact-plate carried by such casing.

11. In a surgical vibrator, the combination with a casing having a handle, of a contact-plate hinged thereto, and a rotary striker mounted in said casing and comprising a body having one or more heads integral therewith but yieldingly connected thereto and effective to engage said plate. 45
12. In a surgical vibrator, the combination with a casing having a handle, of a contact-plate hinged thereto, a rotary striker mounted in said casing and comprising a body having one or more heads integral therewith but yieldingly connected thereto and effective to engage said plate, and a flexible shaft connected with said striker for imparting motion thereto. 50
13. In a surgical vibrator, the combination with a casing open at its under side; a plate hinged to such casing at such under side; a shaft journaled in said casing and having a threaded portion and a shoulder; a striker having an internally-threaded bearing-sleeve for the reception of the threaded portion of said shaft; means comprising a nut and washers for securing said striker in position; and a flexible shaft connected with said striker-shaft for imparting motion thereto. 55
14. In a surgical vibrator, the combination with a casing open at its under side, of a plate hinged to such casing at such under side; a shaft journaled in said casing and having a threaded portion and a shoulder; a striker comprising a body having one or more heads integral therewith but yieldingly connected thereto, each of said heads having a cap, said striker having an internally-threaded bearing-sleeve for the reception of the threaded portion of said shaft; means for securing said striker in position; and a flexible shaft connected with said striker for imparting motion thereto. 60
15. As an article of manufacture, a striker comprising a body having one or more heads formed of resilient material and integral therewith, each joined to such body by a neck of less area than such head whereby the head will yield relatively to the body. 65
16. As an article of manufacture, a striker comprising a body having one or more heads integral but yieldingly connected therewith and each having a cap. 70
17. As an article of manufacture, a striker comprising a solid body having a plurality of integral circularly-formed heads projecting radially therefrom but yieldingly connected therewith. 75
18. In a surgical vibrator, the combination of a rotary striker comprising a body formed of resilient material and having one or more heads integral therewith, each joined to such body by a neck of less area than such head whereby the head will yield relatively to the body; a contact-plate in position to coöperate with such head or heads; and means for rotating such striker. 80
19. In a device of the character specified, the combination of a contact-plate; means for supporting the plate; means for vibrating the plate and comprising a body formed of yielding material and having a part thereof encircled by a metallic member constructed to shift the contact-plate; and means for rotating the vibrating means. 85
20. In a device of the character specified, the combination of a contact-plate; means for supporting the plate; means for vibrating the plate and comprising a body formed of a yielding material and carrying one or more plate-engaging surfaces having metallic coverings. 90
